WEB ROLL WINDER

George Baechli, New Philadelphia, Ohio, assignor
to Joy Manufacturing Company, Pittsburgh,
Pa., a corporation of Pennsylvania

Application May 2, 1950, Serial No. 159,631

11 Claims. (Cl. 242—58)

1

This invention relates to a web roll winder, particularly to a winder such as is used in underground mines in connection with the belt of a belt conveyor, which belt must be moved about from one location to another and which must be wound and unwound repeatedly.

The mining industry today uses conveyor belts extensively. Belts for these conveyors are supplied rolled up in lengths usually 250 feet long. Conveyor belts are heavy and are handled manually with a great deal of difficulty.

It is an object of this invention to provide a web roll winder adaptable to belts, which is easily maneuvered in mines and which readily permits handling of a belt in connection with setting up and taking down a belt conveyor.

This and other objects are accomplished in a web roll winder which is capable of taking a belt roll and mounting it for rotation about a horizontal axis, orienting that axis about a vertical axis to align the strip of belting in any desired direction, and to permit ready and easy unrolling of the belt, and which provides power-operated means to roll up a belt.

In the drawings:

Fig. 1 is a top plan view of a belt winder made according to this invention.

Fig. 2 is a side elevation view of the winder shown in Fig. 1.

Fig. 3 is an end elevation view with the end plate broken away to show details of the mechanism.

Fig. 4 is a partial view in section on line 4—4 of Fig. 2, and on a larger scale.

Fig. 5 is a top plan view of the support and the track-providing means, the base and track-engaging means and associated equipment not being shown in Fig. 5.

Fig. 6 is a side elevation view of as much of the device as is shown in Fig. 5.

Fig. 7 is a view in section on line 7—7 of Fig. 5.

Fig. 8 is a view in section substantially on line 8—8 of Fig. 1, and on a larger scale than Fig. 1.

Fig. 9 is a view in section on line 9—9 of Fig. 1, and to the same scale as Fig. 8.

Fig. 10 is a view in section on line 10—10 of Fig. 9.

Fig. 11 is a view in section on line 11—11 of Fig. 8; and

Fig. 12 is a diagram of the hydraulic circuit.

The support

As shown in this embodiment, the winder is adapted to travel on rails 2, but it will of course be understood that it need not be a rail-mounted device. The rails 2 are engaged by flanged wheels 4. It will be noted that the wheels 4 are very small, in order to keep the overall height of the winder to a minimum. The wheels 4 are adapted to provide a rolling carriage for

2

a support indicated at 6 by means of axles 8. As is best seen in Fig. 4, the wheels 4 rotate on bearings 10 provided on the ends of axles 8, and between a collar 12 welded to the shaft and another collar 14 held on the shaft by a cotter pin 16. Lubrication for the wheel is provided by means of a suitable lubricant fitting 18 communicating with passages 20 and 22 in the axle and a groove 24 in the bearing.

The axles 8 are supported in box sections 26 consisting of a pair of channels 28 welded together. The box sections are rigidly held together by cross members 30, 32 and 34, which are preferably channel members welded at their ends to the box sections 26.

A track-providing means 36 consisting of a substantially circular angle iron is mounted on the support 6. To this end, cantilever arms 38 are provided at the sides and substantially midway between the ends of box sections 26. Each arm 38 preferably comprises a rib 40 welded to the outer faces of the box sections 26, and a top plate 42 welded also to its associated box section 26 and to the upper edge of rib 40.

As is perhaps best seen in Fig. 7, each rib 40 is provided with a projection 44 extending upward, to which the track-providing means 36 is secured. The track-providing means 36 is supported on the box section members 26 by means of spacers 46 and on the cross members 30 and 34 by means of spacers 48. To add strength and rigidity to the entire support structure, triangular reinforcement plates 50 are secured in the corners formed by the cross members 30, 34 and the box section members 26.

The base

The belt winder includes a base indicated generally at 52. Means are provided pivotably to mount the base on the support about a substantially vertical axis, the means including the track-providing means just described and track-engaging means consisting of rollers 54 rotatably mounted on the base and in engagement with the track-providing means 36.

Rollers 54 are rotatably mounted on base 52 by being secured to a bottom plate 56 of the base by means of a pair of bracket members 58 spaced apart by a block 60. Bracket members 58 and block 60 are preferably welded together to provide a support for the axle 62 of the roller 54. The brackets 58 are welded to the under side of bottom plate 56.

A plurality of longitudinal reinforcing members 64 are secured as by welding to the under side of bottom plate 56. The reinforcing members 64 preferably run the length of the plate 56 and may be of any suitable number, although four such members are shown in this embodiment. On the upper surface of plate 56 there

are mounted end members indicated generally at 66 and 68. The members 66 and 68 are also preferably welded to the plate 56.

End member 66 consists of a pair of parallel plates 70 and 72. A top plate 74 is secured to the upper ends of the plates 70, 72 and holds them spaced apart. In addition, two short lengths of channel 76 (Figs. 2 and 8) are welded between the plates 70, 72 to space them apart and provide the desired rigidity.

Similarly, upright member 68 consists of plates 78 and 80 spaced apart by short lengths of channel, one of which is shown at 82, and provided at their upper end with a top plate 84.

With the help of bearings indicated generally at 86 and 88, the two upright members 66 and 68 serve as means on the base rotatably to mount a web roll on a substantially horizontal axis. As is readily seen in Fig. 8, bearing 86 comprises a base 90 welded to the top plate 74, a bottom bearing half 92 and a top bearing half 94. The two bearing halves are hingedly connected together by a hinge link 96. The link 96 engages the bearing halves 92 and 94 by means of pins 98 and 100 respectively. At their opposite ends, the two bearing halves 92 and 94 are secured together by a bolt and nut arrangement 102, the bolt of which is hinged to bearing half 92 and fits in a slot in the bearing half 94, the nut thereof engaging the upper surface of bearing half 94. The two bearings 86 and 88 are substantially identical.

The bearings 86 and 88 support a web roll spindle or shaft 104. Shaft 104 is preferably square, except for its left end as seen in Fig. 2, where it engages bearing 86, and a portion near its right end where it engages bearing 88. Between the bearings, shaft 104 carries a belt core 106 which is provided with a pair of belt lacing pins 108 and 110. The two pins 108 and 110 are of different sizes and are adapted to engage lacings of two different sizes. Pins 108 and 110 are removably mounted on the core 106 in any suitable manner.

The right end of shaft 104 engages a simple square coupling 112 which couples the shaft 104 to a drive shaft 114. The coupling 112 may be nothing more than a square sleeve receiving in its opposite ends the square ends of shafts 104 and 114. Sleeve 112 is simply slidable axially along shaft 104 to effect coupling and uncoupling of shaft 104 with shaft 114.

Shaft 114 is the output shaft of a hydraulic drive for core 106, consisting of the bevel gear drive 116, gear reduction 118, hydraulic motor 120 and the chain and sprocket connection 122. Hydraulic motor 120 connects with pump 124 by means which will be described below and which are shown in Fig. 12.

The transport

The base is provided with additional means to support a web roll, the additional means being movable vertically with respect to the base. The additional means referred to may be called a transport and is best shown at 126 in Figs. 1, 2, 9 and 10.

The transport 126 comprises end members 128 and 130, a floor member 132 and side members 134 and 136 secured to the floor member by any suitable means, as for example by welding, the side members being adapted to block a web roll against rolling off the transport.

The transport 126 is provided to have vertical movement with respect to the base 52, as set forth

above. Guide means are provided to assure movement of the transport along a desired path. The guide means consists of a guide slot 138 and a guide block 140 for each end of the transport. In the embodiment shown, slots 138 are provided in the plates 72 and 78 and the guide blocks 140 are provided on the end members 128 and 130. Each guide block 140 consists of a spacer block 142 and a hanger 144 bolted to the end member 128 or 130. As is best seen in Fig. 10, the spacer block 142 is somewhat thicker than the plate 78 in order to assure that the parts will not bind during vertical movement. The hanger 144 is wider than slot 138 and thus restrains the transport 126 against longitudinal movement. Hanger 144 is also provided with a projection 146.

A flexible tension member is provided at each end of the transport in order to lift the transport with a web roll on it. In the embodiment shown, the flexible or tension member consists of a chain 148 having one end secured to the projection 146. The chain is connected to be put in tension by being wrapped around a shaft 150. The connection which wraps the chain around the shaft consists of sprocket wheel 152 mounted on shaft 150 for rotation therewith, and of course there is such a sprocket wheel at or near each end of shaft 150. Shaft 150 is mounted for rotation on base 52 in bearings 154.

In order that the shaft 150 may be located in such a place as not to interfere with the web roll, the shaft bearings 154 are mounted on the bottom plate 56 to one side of the transport 126. In order with this arrangement to be able to put tension in the chains 148 by wrapping them around the shaft 150, idler wheels 156 are rotatably mounted on the base. As shown, the idler wheels 156 are rotatably mounted adjacent slots 138 in the upright end members 66 and 68 by being journaled on shafts 158. One of these shafts 158 is carried by the plates 70, 72 and the other is carried by the plates 78, 80. Spacer sleeves 160, cotter pins 162, and spacer washers 164 are provided to hold the shafts 158 in place. It will of course be understood by those skilled in the art that the idler wheels 156 are preferably sprocket wheels.

Means are provided to turn or rotate the shaft 150 in order to put tension in the chains 148, whereby to lift the transport. To this end, a third flexible or tension member is adapted to wrap around shaft 150 to turn it. In the embodiment shown, this third tension member or flexible member preferably consists of a length of cable 166, having one end connected to turn shaft 150 by means of a pulley 168 to which the cable is secured, and having another end adapted to be anchored to the base as shown in dotted lines at 170 in Fig. 1.

Between the ends of the cable 166 means are provided to put the cable in tension, consisting of a hydraulic jack 172 (Fig. 8) having a piston rod 174 which carries a pulley 176. Cable 166 passes around pulley 176 in such a manner as to be put in tension when fluid is admitted under pressure to the left end of jack 172 by way of the fluid connection 178. Another fluid connection 180 is provided at the opposite end of the hydraulic jack.

The jack 172 is pivotally mounted at one end by means of a bracket 182 welded or otherwise suitably secured to bottom plate 56, and a pivot pin 184 engaging a tongue member 186 on the

The hydraulic system

A belt winder made according to this invention is preferably powered by hydraulic means, for a description of which reference will now be had particularly to Fig. 12, inasmuch as the necessary hose connections are not shown in the other figures. The hydraulic pump 124 is shown in the hydraulic system diagram of Fig. 12. Pump 124 is connected, as for example by the V-belt drive 192, to be driven by electric motor 194, motor 194 preferably being mounted on a base 196 which in turn is carried by upright plates 80 and 198 (Figs. 2 and 3).

Pump 124 is preferably two pumps in one casing. These two pumps, or pump sections, will be designated by the numerals 200 and 202. Preferably, one of these pumps will be bigger than the other. In the embodiment shown, the pump section 200 is assumed to be a 2-inch pump and the pump section 202 a 1-inch pump, although of course it is to be understood that these are merely examples and that other pump sizes may be used.

Control valves 204 and 206 are shown. A conduit 208 connects the discharge of pump section 200 with control valve 204 and a conduit 210 connects the discharge of pump section 202 with the control valve 206. The exhaust of control valve 206 is connected by a conduit 212 with a reservoir 214. A conduit 216 connects the exhaust of valve 204 with the reservoir by way of a portion of conduit 212. Both pump sections 200 and 202 have their suctions connected with a common intake, which is connected with reservoir 214 by a conduit 218.

Control valve 204 is adapted to admit fluid under pressure to a third control valve 220 by way of a conduit 222. Control valve 206 is connected to admit fluid under pressure to control valve 220 by way of a portion of the same conduit 222 and a branch conduit 224. The exhaust of control valve 220 is connected with reservoir 214 by conduits 226, 228 and a portion of conduit 212.

One of the control sections of control valve 220 is connected with the two fluid connections 178 and 180 of jack 172 by means of conduits 230 and 232, respectively. Another control section of valve 220 is connected to hydraulic motor 120 by way of a conduit 234. The exhaust of the hydraulic motor 120 is connected by a conduit 236 with the exhaust conduit 228.

Operation

A web roll winder made according to this invention will generally be used in a train with a number of cars adapted to carry a plurality of rolls. In the application of the invention envisaged by the applicant, the web rolls handled by the invention are belt rolls, for example the belting that is used in belt conveyors.

A train goes to a belt conveyor location including in its train a belt winder made according to this invention and one or more belt carrier cars. When the location for a conveyor is reached, a roll of belting is removed from the carrier car to the belt winder. This is done by turning the base on its vertical axis until it is oriented in such a manner that a roll of belting may be easily rolled onto the transport 126. The roll of belting is of course rolled into place with the core 106 and spindle 104 removed from the bearings 86 and 88.

The transport is then raised in order to bring the belt center above the bearings 86 and 88. Raising of the belt is accomplished by admitting fluid under pressure to the left end of hydraulic

jack 172 as seen in Fig. 8. The pulley 116 will be moved to the right, unwrapping the cable 166 from the pulley 168, thus rotating shaft 150 and wrapping the chains 148 around their sprocket wheels 152. This lifts the transport 126 vertically by virtue of the guides 138 and guide blocks 140. When the belt roll has been raised as high as necessary, fluid is trapped in the cylinder 172. The square shaft or spindle 104 is thereupon thrust through the belt core, and the belt roll is lowered until the cylindrical portions of the shaft 104 fit in the bearings 86 and 88. These bearings are thereupon capped or closed and bolted together.

The transport is lowered the rest of the way to drop it out of contact with the roll of belting. The base 52 is again turned about its vertical axis until the belt is aligned with the conveyor. The belt is then ready to be unbanded and to be unrolled onto the conveyor as will be well understood by those skilled in the art.

Let it now be assumed that a section of belting is to be removed from a belt conveyor. A belt winder according to this invention is pulled to a stop as close to the conveyor as is possible and the base is swivelled on its vertical axis until it is aligned with the belt line of the conveyor. The belt on the conveyor is unhooked by "breaking" the belt at a lacing, and the upper run end of the belt is connected to the core 106. The connection is made by passing one or the other of the pins or rods 108, 110 through the belt lacing, depending on the size of the belt lacing. The belt is then ready to be wound onto the core 106.

A belt winder made according to this invention can be used to pull the tail piece of the conveyor along the mine bottom. With the end of the belt connected as aforesaid, power is applied to the hydraulic motor 120. It will be understood by those skilled in the art that, at the outset, the radius about which the belt winds is relatively small, and a relatively high torque is available with only one of the pump sections 200, 202. Accordingly, the pump section which is not to be used will merely by-pass oil through its control valve.

Let it be assumed that pump section 202 suffices at the start to wind up the belt and drag the tail piece. In that case, pump section 200 will simply by-pass oil through its control valve 204, and pump section 202 will pump oil under pressure to the hydraulic motor by way of conduit 210, through control valve 206, conduits 224 and 222, control valve 220, and conduit 234. Fluid returns from the hydraulic motor by way of conduits 236, 228, and 212, reservoir 214, and conduit 218 back to the pump intake. As the belt piles up on the core, the radius of the belt roll increases to the point where the pump 202 cannot supply the necessary torque. If then pump 200 can supply more than the torque required, pump 202 will be allowed to by-pass oil through its control valve 206 and pump 200 will then drive the hydraulic motor by way of conduit 208, control valve 204, conduit 222, etc. as before. As the belt continues to wind up on the core the belt roll radius continues to increase until pump section 200 cannot supply the necessary torque, whereupon both pump sections 200 and 202 are utilized to drive the hydraulic motor.

It will be obvious to those skilled in the art that flexible tension members 148 and 166 cannot transmit compressive forces. In other words, the transport 126 will have to move downward by the influence of gravity. Nevertheless, the

7
hydraulic jack 172 is preferably made a double-acting jack in order that the piston rod 174 may be powered leftward as seen in Fig. 8. This makes it possible to eliminate sticking of the jack and does not limit the operator to the force of gravity in moving the jack parts to effect lowering of the transport 126.

A web roll winder made according to this invention provides means for handling heavy belt rolls completely by power, thus obviating the tedious, awkward, and often dangerous handling of heavy rolls of belting underground where maneuvering space is often very limited. A belt winder made according to this invention operates with very low head room and is exceedingly flexible 15 in its application. Other advantages will be apparent to those skilled in the art.

While there is in this application specifically described one form which the invention may assume in practice, it will be understood that this form of the same is shown for purposes of illustration, and that the invention may be modified and embodied in various other forms without departing from its spirit or the scope of the appended claims.

I claim:

1. A web roll winder comprising: a base; means on the base rotatably to mount a web roll on a substantially horizontal axis; additional means on the base to receive and support a web roll, including a transport and means to guide the transport for movement vertically with respect to the base and the first-named web roll mounting means; power-operated means to move the transport in accordance with the path prescribed by the guide means, including at least one chain-and-sprocket wheel mechanism comprising an idler wheel rotatable about a fixed axis, a shaft rotatable about a fixed axis, a sprocket wheel mounted on the shaft and rotatable with the shaft, a chain fixed at its ends to the transport and the sprocket wheel and engaging both the idler and the sprocket wheels; and means to rotate the shaft, including a length of cable having one end connected to wrap around the shaft and having its other end anchored with respect to the base, and means engaging the cable between its ends to put tension in the cable.

2. The winder of claim 1, in which the last-named means includes a pulley around which the cable passes, and hydraulic means to move the pulley.

3. The winder of claim 2, in which the hydraulic means includes a jack having a piston rod on which the pulley is rotatably mounted.

4. A web roll winder comprising: a base; means on the base rotatably to mount a web roll on a substantially horizontal axis; additional means on the base to support a web roll and being movable vertically with respect to the base; means to move the additional means vertically, including a transport, at least one chain-and-sprocket wheel mechanism comprising a sprocket wheel rotatable about a fixed axis, and a chain fixed at its ends to the transport and the sprocket wheel and engaging the sprocket wheel, and means to rotate the sprocket wheel, including a cable connected to effect rotation of the sprocket wheel and means to put tension in the cable.

5. A web roll winder comprising: a base; means on the base rotatably to mount a web roll on a substantially horizontal axis; additional means

on the base to support a web roll and being movable vertically with respect to the base; means to move the additional means vertically, including a transport, at least one chain-and-sprocket wheel mechanism comprising a sprocket wheel rotatable about a fixed axis, and a chain fixed at its ends to the transport and the sprocket wheel and engaging the sprocket wheel; cable means connected to rotate the sprocket wheel; and a fluid pressure operated cylinder connected to put tension in the cable.

6. A web roll winder comprising: a base; means on the base rotatably to mount a web roll on a substantially horizontal axis; additional means on the base to support a web roll and being movable vertically with respect to the base; means to move the additional means vertically including a wheel and a length of a flexible member having one end secured to the wheel and adapted to be wrapped around the wheel and having another end secured to the additional means to support a web roll; a second flexible member connected to rotate the wheel; and fluid pressure operated means connected to put tension in the second flexible member.

7. A web roll winder comprising: a base; means on the base rotatably to mount a web roll on a substantially horizontal axis; additional means on the base to support a web roll and being movable vertically with respect to the base; means to move the additional means vertically including a shaft mounted on the base and rotatable about a substantially horizontal axis and a length of a flexible member for each end of the shaft and having one end connected to be wrapped around the shaft and another end connected to said additional means; and means to rotate the shaft.

8. The winder of claim 7, in which the last-named means includes a third flexible member connected to rotate the shaft, and fluid pressure operated means to put said third member in tension.

9. The winder of claim 8, in which there is one idler wheel rotatably carried by the base for each of the two first-named flexible members, said idler engaging its associated flexible member between the ends of that member.

10. The winder of claim 9, in which the fluid pressure operated means carries a reciprocable pulley, the pulley being in engagement with the third flexible member between its ends, one end of the third flexible member being connected to rotate the aforesaid shaft and the other end being anchored to the base.

11. The winder of claim 10, in which the two first-named flexible members are chains, said shaft being provided with sprocket wheels to which the chains are attached to be wrapped around the shaft as aforesaid.

GEORGE BAECHLI.
